UNITED STATES PATENT OFFICE.

VICTOR LAMBERT, OF BROOKLYN, NEW YORK.

CAN OPENER.

Application filed September 8, 1921. Serial No. 499,275.

To all whom it may concern:

Be it known that I, VICTOR LAMBERT, a citizen of the United States, residing at Brooklyn, in the county of Kings, State of New York, have invented certain new and useful Improvements in Can Openers; and I do hereby declare the following to be a full, clear, and exact description of the invention, such as will enable others skilled in the art to which it appertains to make and use the same.

This invention relates to a can opener of the type designed for cutting the sides of a can so as to completely remove the top thereof and lay open the entire interior of the can, and involves the provision among other features of novel fastening means whereby the cutter may be readily adjusted and fixed in cutting position.

Can openers of the type referred to heretofore constructed either provide no means for holding the cutting blade of the opener against the can while the cutting operation is being performed, the operator being obliged to apply and hold the blade against the can by hand, or the fastening means provided for setting the blade in cutting position and locking it in that position are ineffective as where a spring is employed, or too expensive for an article of this sort as where cams and ratchet teeth are employed.

One of the principal objects of this invention therefore is to provide a can opener of the type described, consisting of a minimum number of parts, simple in design and construction so that the tool may be readily manufactured and assembled at minimum cost. The invention aims particularly to provide a simple and effective fastening means for setting the cutting blade of the can opener and locking it in operative position so that the cutting operation may be performed without the necessity of the cutter being held by the operator and forced against the can and without shifting of the cutter relative to the shank of the tools.

The can opener comprises a shank having a centering point at one end which is inserted in the top of the can prior to the cutting operation to properly position the tool and provide a pivot point therefor. The shank has guides near its end opposite that on which the centering point or punch is secured in which a cutter bar is slidably mounted. In order that the cutter bar may be adjusted and fixed in proper cutting po-

sition on the shank without being held by the operator means are provided comprising a clamp pivoted on the cutter bar and having projecting edges on its inner side which are adapted, upon turning of the clamp, to engage the outer surfaces of the guides and grip them. The projecting edges may be formed by beveling the inner sides of the clamp and preferably the taper of the beveled surfaces is of increasing thickness in the direction of turning of the clamp terminating in sharp edges which are adapted to engage the outer surfaces of the guides, the latter preferably being provided with knurling to enhance the gripping action. In the preferred form of construction the guides for the cutter bar carrying the cutting blade are formed by bending over projecting lateral edges of the shank formed in stamping the latter and these bent over edges are curved so that the curvature thereof increases toward the edges of the shank. The maximum height, therefore, of the guides above the surface of the shank will be along the edges thereof where the greatest gripping action between the clamp and the outer surfaces of the guides will take place.

In order that the edges of the can along the incision made by the opener shall be smooth and free from jagged projections rendering the subsequent handling of the can dangerous, the cutting blade is preferably provided with beveled edges which operate to turn in the edges of the can as the incision by the blade progresses, thus producing not only a smooth upper edge on the can, but also the edge of the top removed.

The invention is illustrated in the accompanying drawings in which—

Fig. 1 is a plan view of the underside of the can opener;

Fig. 2 is a side view of the can opener illustrated in Fig. 1;

Fig. 3 is a view along the line 3—3 of Fig. 2; and

Fig. 4 illustrates the can opener applied to a can in operative position.

The shank 5 of the can opener consists of a flat bar having riveted on one end as at 6 a centering point or punch 7. Near the opposite end of the bar 5 are a pair of guides 8 which, in the construction shown, are formed by bending over lateral extensions of the bar 5 formed in stamping out

this piece. Beneath the bar 5 and slidably mounted in the guides 8 is a cutter bar 9. One end of this bar has riveted thereto as at 10 a cutter 11 and both ends thereof are bent at right angles. The upwardly bent edges of the cutter bar 9 on either side of the cutter 11 provide a stop 12 to limit the inward thrust of the cutter when the can opener is applied to a can in operative position. The bent over edge 13 at the opposite end of the cutter bar provides a finger hold by which the cutter bar may be grasped to adjust it in cutting position for cans of varying diameter.

15 For the purpose of adjusting the cutter bar 9 relative to the shank 5 in accordance with the size of the can to be opened, and to fix the cutter bar in the adjusted position, the latter has pivoted thereto at 13 a clamp 20 14, the pivot 13 comprising a pin having a shank of a length such as to permit the clamp to engage the outer surfaces of the guides 8 and to force the cutter bar against the under edges of the guides when the 25 clamp is turned in the position illustrated in Fig. 1 thus producing a binding action between the shank and the bar so that the latter will be held in adjusted position. In order that the gripping action between the 30 clamp and the outer surfaces of the guides 8 may be sufficient to firmly hold the cutter bar 9 in adjusted position on the shank 5, the under side of the clamp 14 is provided with bevels or tapering projections 35 15 disposed one on each side of the pivot 13, the projections tapering or increasing in thickness in the direction of turning of the clamp 14 and terminating in sharp edges which bind against the upper surfaces of the guides 8 and drawing the cutter bar 9 against the guides with a force sufficient to fix the bar in cutting position. The binding 40 action between the clamp 14 and the outer surfaces of the guides 8 is enhanced by forming the guides so that the outer surfaces thereof will be curved and of an increasing curvature toward the edges of the shank as shown in Fig. 3, and also by providing the outer surfaces of the guides with 45 knurling as at 16.

50 The operation of the can opener will be readily understood from an inspection of Fig. 4, which illustrates the tool applied to a can in cutting position. The bar 9 is first loosened by turning the clamp 14 to a position approximately parallel with the guides 8, and to facilitate the turning of the clamp the latter is provided with knobs or finger holds 17. The cutter bar having been released, the cutter 11 is brought back to an 55 approximate cutting position and the centering point or punch 7 is inserted in the top of the can. The cutter bar is now adjusted to bring the cutter 11 in proper position to 60 cut the side of the can as shown in Fig. 4, 65

and is fixed in this adjusted position by turning the clamp 14. The inward adjustment of the blade 11 in cutting position is limited by the stop 12 so that the cutter will be prevented from entering the can beyond the position fixed by the stop. The binding action between the bar 9 and the guides 8 produced by the interaction between the tapering projections on the inner side of the clamp and the outer knurled surfaces of the guides 8 will be sufficient to firmly hold the bar 9 from shifting while the cutting operation is being performed. At the same time while providing a rigid locking means between the bar 9 and the shank 5, the bar may be readily released and removed for cleaning simply by turning the clamp 14, in this case in a counter clockwise direction until the wings of the clamp are nearly parallel with the guides. It will be readily understood that the taper given to the projections on the inner side of the clamp 14 is designed for right hand turning of the clamp, or turning in a clockwise direction. By giving to the projections a slant in the opposite direction the same progressive tightening action between the clamp and the outer surfaces of the guides might be obtained by turning the clamp to the left or in a counter clockwise direction. The bent over edge 13 of the bar 9 may be provided with an aperture 18 so that the tool may be hung upon a hook.

100 In place of providing a separate cutter 11 riveted on the cutter bar 9, as in the construction illustrated, the cutter bar might readily be stamped to provide projecting knife edges so that the cutter would be integral with the bar. Where the cutting edges are beveled as illustrated in the drawings, the edges of the can produced by the cut will be slightly turned in so as to provide a smooth edge and thus remove all danger incident to the subsequent handling 105 of the can as would otherwise be the case if the edges produced by the incision of the can opener were allowed to remain sharp or jagged.

110 I claim—

115 1. A can opener comprising a shank having a centering point at one end and guides near its opposite end, a cutter bar slidably mounted in said guides, and means for adjusting and fixing said cutter bar on the shank comprising a clamp pivoted on said cutter bar and having projecting edges on its inner side adapted, upon turning of the clamp, to engage the outer surfaces of said guides whereby to grip them and hold the cutter bar in operative position.

120 2. A can opener comprising a shank having a centering point at one end and guides near its opposite end, a cutter bar slidably mounted in said guides, and means for adjusting and fixing said cutter bar on the

- shank comprising a clamp pivoted on said cutter bar and having beveled inner sides providing edges adapted, upon turning of the clamp, to engage the outer surfaces of 5 said guides whereby to grip them and hold the cutter bar in operative position.
3. A can opener comprising a shank having a centering point at one end and guides near its opposite end, a cutter bar slidably 10 mounted in said guides, and means for adjusting and fixing said cutter bar on the shank comprising a clamp pivoted on said cutter bar and having tapering projections on its inner side increasing in thickness in 15 the direction of turning and terminating in sharp edges adapted to engage the outer surfaces of said guides whereby to grip them and hold the cutter bar in operative position.
4. A can opener comprising a shank, a centering point at one end of said shank and guides near the opposite end thereof, said guides having knurled outer surfaces, a cutter bar 20 slidably mounted in said guides, and means for adjusting and fixing said cutter bar on the shank comprising a clamp pivoted on said cutter bar and having tapering 25 projections on its inner side increasing in thickness in the direction of turning and terminating in sharp edges adapted, upon turning of the clamp, to engage the knurled surfaces of said guides whereby to grip them and hold the cutter bar in operative position.
5. A can opener comprising a shank having at one end a centering point and bent over lateral edges near the opposite end forming guides having curved outer surfaces 30 of increasing curvature near the edges of said shank and provided with knurling, a cutter bar slidably mounted in said guides, and means for adjusting and fixing said cutter bar on the shank comprising a clamp pivoted on said cutter bar and having tapering 35 projections on its inner side increasing in thickness in the direction of turning, and terminating in sharp edges adapted to engage the outer surfaces of said guides whereby to grip them and hold the cutter bar in operative position.
6. A can opener comprising a shank having a centering point near one end and guides near its opposite end, a cutter bar 40 slidably mounted in said guides and having at one end a cutter provided with downwardly beveled cutting edges, and means for adjusting and fixing said cutter bar on the shank comprising a clamp pivoted on said cutter bar and having projecting edges on its inner side adapted, upon turning of the 45 clamp, to engage the outer surfaces of said guides whereby to grip them and hold the cutter bar in operative position.
7. A can opener comprising a shank having a centering point at one end and guides near its opposite end, a cutter bar slidably mounted in said guides and having at one 50 end a cutter provided with downwardly beveled cutting edges and a stop at the inner end of the cutter, and means for adjusting and fixing said cutter bar on the shank comprising a clamp pivoted on said cutter bar and having projecting edges on its inner side adapted, upon turning of the clamp, to engage the outer surfaces of said guides whereby to grip them and hold the cutter bar in 55 operative position.
- In testimony whereof I affix my signature.

VICTOR LAMBERT.
